PACKAGE FOR MILK AND OTHER FLUID PRODUCTS

Samuel H. Berch, Beverly Hills, Calif., assignor to
Flexible Container Corporation, Los Angeles,
Calif., a corporation of Nevada

Application June 24, 1941, Serial No. 399,497

2 Claims. (Cl. 229—7)

This invention relates to a package and particularly pertains to a package for milk and other fluid products.

In packaging various fluid products, it is desirable to provide an inexpensive container within which the fluid, such as milk, may be vacuum sealed to maintain the milk in a sterile condition and to prevent the growth of bacteria. It is also desirable to provide a non-metallic carton which may be easily opened in a manner to form a pouring spout and after which the spout may be closed and held in its closed position to maintain the contents of the container sanitary. It is the principal object of the present invention, therefore, to provide a carton into which fluid material may be introduced and within which the product may be vacuum sealed, the carton being formed with a pouring spout which is sealed within the structure to be thus maintained sanitary, and which may be opened and closed as desired.

The present invention contemplates the provision of an outer semi-rigid carton, within which is disposed a collapsible vacuum-tight package or liner sealed independently of the carton and cooperating therewith to provide a sanitary spout and closure means therefor.

The invention is illustrated by way of example in the accompanying drawings, in which:

Figure 1 is a view in perspective showing the container when it has been opened and is in its pouring position.

Fig. 2 is a fragmentary view in perspective showing the end of the container and the manner in which the pouring spout is initially sealed.

Fig. 3 is a fragmentary view similar to Fig. 2, showing the manner in which the pouring spout is sealed after it has once been opened.

Fig. 4 is an enlarged fragmentary view in longitudinal section as seen on the line 4—4 of Fig. 3 and discloses the details of construction of the outer carton and the inner bag.

Fig. 5 is a view in plan showing the carton blank.

Fig. 6 is an end view showing the assembled carton.

Fig. 7 is a view in plan showing the blank for the inner liner or bag.

Fig. 8 is an end view showing the assembled bag or liner.

Fig. 9 is a fragmentary view in perspective showing the bag in its opened position preparatory to filling.

Fig. 10 is a perspective view showing the sealing operation of the liner.

Fig. 11 shows the bag after it has been filled and sealed and discloses the manner in which the ends are folded into the carton.

Fig. 12 is a view in perspective showing the pouring end of the bag and the position of the carton and bag parts prior to the time when they are initially sealed.

Referring more particularly to Fig. 5 of the drawings, it will be seen that the carton blank 10 is formed with side panels 11, 12, 13 and 14, which are separated by longitudinal score marks 15, 16 and 17. Adjoining the panel 14 and separated therefrom by a longitudinal score line 18 is a longitudinal sealing flap 19. The lower ends of the panels are defined by a transverse score line 20, and the upper ends are defined by a transverse score line 21. Beyond the lower transverse score line 20 of the panels 11 to 14, inc., are sealing flaps 22, 23, 24 and 25, which form the bottom end of the sealed container. The side edges of the sealing flaps 22 and 24 are formed as continuations of the score lines 15, 16 and 17. The side edges of the flaps 23 and 25 are offset from the score marks so that the sealing flaps 23 and 25 are of slightly lesser width than the flaps 22 and 24, whereby clearance spaces are provided for a purpose to be hereinafter specified. The upper transverse score line 21 divides the side panels from sealing flaps 26, 27, 28 and 29. The sealing flaps 21 and 29 agree in size and shape with the sealing flaps 23 and 25. The sealing flap 26 agrees in size and shape with the sealing flap 22. The flap 28, however, which is on the opposite end of panel 13 from the sealing flap 24 is different from the other sealing flaps in that it is scored and shaped to provide a sealing tab for the top of the package. In general, this flap is rectangular in shape. It, however, has a projecting tab 30 which is tongue shaped and is partially separated from the body of the flap 28 by opposite parallel perforated score marks 31 and 32 and diagonal perforated score marks 33 and 34 which join the score marks 31 and 32 and define two corner fields 35 and 36. A center score mark 37 extends from the score line 21 of panel 13 centrally of the flap 28 and the tab 30. Diagonal score marks 38 and 39 form continuations of the diagonal perforated score marks 33 and 34 for a purpose to be hereinafter described.

The blank 10 may be formed of any desired material. It has been found suitable to form it of light-weight cardboard, the inner and outer faces of which have been properly treated with 55 a coating material which will render it water-

proof. The carton formed from the blank 10 is folded, as shown in Fig. 6 so that the panel 11 overlaps the longitudinal sealing flap 19 carried by the panel 14. The longitudinal sealing flap is then secured to the panel 11 by some suitable adhesive.

A bag-like liner 40 is provided to be inserted within the carton and to be glued into position. This liner is preferably formed of laminated sheet material comprising an outer sheet of non-stretchable material and an inner sheet of material impervious to moisture and gases, whereby a vacuum sealed bag can be produced. As shown in Fig. 7 of the drawings, a longitudinally extending sheet 41 of this material is provided. It is intended to be folded upon itself upon an intermediate transverse fold line 42, and to thereafter be heat sealed along the marginal fields 43 and 44 to form the seams 45 and 46. It will be evident that when the bag is folded to the rectangular shape, as shown in Fig. 8 of the drawings, and the lower end is squared, the side walls and the end walls will form triangular folded tabs 47 and 48, as shown in Fig. 8 of the drawings. After the liner 40 has been thus shaped it may be inserted into the carton which has been given its sectional form, as shown in Fig. 6. The tabs 47 and 48 are then folded parallel to each other, as shown in Fig. 12, and are secured to the upper end sealing flaps 26 and 28, respectively, after which the upper end sealing flaps 27 and 29 may be sealed down against the end of the liner 40. The flap 26 is then sealed down onto the flaps 27 and 29, and the flap 28 is sealed into position with the tongue 30 overlapping the edge of the flap 26, as shown in Fig. 2 of the drawings. The container with its liner thus formed is then ready for filling.

The condition of the opposite end of the carton and liner at this stage of its formation is disclosed in Fig. 9 of the drawings. It is to be understood that the previously sealed and formed end of the package will be the top of the package when dispensed, and that the package is filled through the bottom while inverted. In Fig. 9 it will be seen that the opened mouth of the liner 40 projects above the end of the sealing flaps 22 to 25, inc. The package may then be filled in suitable filling apparatus and thereafter subjected to a vacuum action, after which the mouth of the liner 40 may be compressed to form a sealing portion 49, as shown in Fig. 10. When this sealing portion has been compressed the mouth of the liner will be sealed since the inner rubber faces are brought into contact with each other and the application of heat is made. Thus, the product within the inner liner is vacuum sealed and the sealed portion 49 may be folded down while the triangular members 50 and 51 of the liner will lie outwardly over the sealing flaps 22 and 24. While in this position adhesive may be applied to secure these triangular portions to the sealing flaps 22 and 24, after which sealing flaps 23 and 25 may be folded down on the end of the filled liner, and then the flaps 22 and 24 may be folded down and secured by some suitable adhesive. It will thus be seen that the filled container is vacuum sealed and ready for commercial use.

When it is desired to open the container the edge of the tongue 30 may be pried away from the end of the sealing flap 26 and from the position shown in Fig. 2. As this is done the tongue 30 will break the lines of perforation 31, 32, 33 and 34, and will leave the portions 35 and 36 of 75

the sealing flap 28 secured to the sealing flaps 27 and 29. It will be seen that when this is done the tongue 30 may be pulled downwardly, thus uncovering the slit formed between the contiguous edges of the sealing flaps 27 and 29 and bending the triangular portion 48 of the liner 40 outwardly and downwardly. The apex of this triangular portion may then be cut off by scissors or the like to form an opened slit 52 in the liner portion 48. The sides of the container may then be pressed at the corners of the triangular portion 48 so that the end of the container will bulge outwardly and will cause the slit 52 to open sufficiently to allow the fluid to be poured therethrough. When a sufficient quantity of fluid has been poured pressure may be relieved and the tongue 30 may then be folded against the end of the box with its free end tucked under the edge 53 of the sealing flap 26. This will maintain the container sealed and the material therein in a sanitary condition.

The package may be vacuumized and sealed in a mold structure such as I have shown in my pending application entitled "Method of packing food products and the like," Serial No. 210,038, or in some other type of apparatus. It will be evident that when a flexible package such as that represented by the inner liner 40 is vacuum sealed, the surrounding atmospheric pressure tends to collapse the package and compact the material therein, whether it be liquid, powder, granular material, or a solid. This may cause the package to be irregular in form. In the present instance, however, the flexible bag comprising the inner liner 40 is secured to the outer carton at its ends only and is free to collapse along its sides, and since the side walls of the collapsible package are independent of the side walls of the outer container, the outer container will retain its uniform size with straight sides and straight corners.

It will thus be seen that the container here disclosed may be inexpensively manufactured, and will insure that perishable products, such as milk, may be vacuum sealed and maintained in a desired condition of freshness and sanitation for long periods of time, and that furthermore, the container may be easily opened and thereafter sealed.

While I have shown the preferred form of my invention as now known to me, it will be understood that various changes may be made in combination, construction, and arrangement of parts by those skilled in the art, without departing from the spirit of my invention as claimed.

Having thus described my invention, what I claim and desire to secure by Letters Patent is:

1. A carton formed from a blank having four main parallel fields scored to provide the four walls of a carton and each field having sealing flaps at its opposite ends, one of said sealing flaps being scored centrally parallel to the opposite edges of the flap and being scored diagonally from the outer edges of the flap at its base to a point of intersection with said intermediate score line, said diagonal score lines being perforated for a length, the flap being further formed with parallel perforated lines at the opposite sides of the center line whereby sealing portions are provided to adhere to the folded flaps of the contiguous side walls, said portions only being sealed thereto, a liner for said container consisting of an open ended tubular element formed of flexible sheet material, the opposite ends of said element being of sufficient length to

extend beyond the side wall folds of the carton substantially the length of the end flaps, the portion of the liner bounded by the side walls adhering thereto, the projecting end portions of the liner being brought together along the median line of the container whereby a separate sealing line of the container will be formed transversely of the end between the contacting inner faces of the liner, said sealed portion being folded to provide opposite triangular end folds projecting beyond the end plane of the carton, the median line of one of said folds coinciding with the median line of the aforementioned scored flap whereby when the scored flap is severed along its lines of perforation the free portion thereof together with the triangular portion of the inner liner may be swung outwardly and the end of the triangular portion of the inner liner severed to provide a pouring spout.

2. A carton formed from a blank having four main parallel fields scored to provide the four walls of a carton and each field having sealing flaps at its opposite ends, the flaps each being of a width representing substantially one-half the width of the carton end, one of said sealing flaps being scored centrally parallel to the opposite edges of the flap and being scored diagonally from the outer edges of the flap at its base to a point of intersection with said intermediate score line, said diagonal score lines being perforated for a length, the flap being further formed with parallel perforated lines at the op-

posite sides of the center line whereby sealing portions are provided to adhere to the folded flaps of the contiguous side walls, said portions only being sealed thereto, said scored flap having a central extension to project beneath the opposing end flap, a liner for said container formed of material impervious to air and moisture, the abutting faces being capable of heat sealing, consisting of an open ended tubular element formed of flexible sheet material, the opposite ends of said element being of sufficient length to extend beyond the side wall folds of the carton substantially the length of the end flaps, the portion of the liner bounded by the side walls adhering thereto, the projecting end portions of the liner being brought together along the median line of the container whereby a separate sealing flap will be formed transversely of the end between the contacting inner faces of the liner, said sealed portion being folded to provide opposite triangular end folds projecting beyond the end plane of the carton, the median line of one of said folds coinciding with the median line of the aforementioned scored flap whereby when the scored flap is severed along its lines of perforation the free portion thereof together with the triangular portion of the inner liner may be swung outwardly and the end of the triangular portion of the inner liner severed to provide a pouring spout.

SAMUEL H. BERIC.
